UNITED STATES PATENT OFFICE.

EDWIN WILBUR RICE, JR., OF LYNN, MASSACHUSETTS.

MOUNTING FOR ELECTRIC-CAR MOTORS.

SPECIFICATION forming part of Letters Patent No. 444,922, dated January 20, 1891.

Application filed August 15, 1889. Serial No. 320,906. (No model.)

To all whom it may concern:

Be it known that I, EDWIN WILBUR RICE, Jr., a citizen of the United States, and a resident of Lynn, in the county of Essex and State of Massachusetts, have invented a certain new and useful Motor-Suspension for Railway-Work, of which the following is a specification.

My invention relates to the manner of mounting or supporting the electric motors employed in connection with railway-cars as a means of propelling the same.

The object of my invention is to secure an unvarying or rigid relation of the parts of the driving mechanism, while at the same time securing flexibility or adaptation to shocks or vibrations of the vehicle.

My invention consists in the novel construction and combinations of mechanism hereinafter described in connection with the accompanying drawings, and then specified in the claims.

In the accompanying drawings, Figure 1 is a side elevation of a railway-car truck having a motor mounted and supported in accordance with my invention. Fig. 2 is a plan of the motor and its supporting devices.

F indicates a frame of any suitable material, consisting of two side pieces and a cross-piece, preferably integral with one another, and having the ends of the side pieces sleeved upon an axle A of the car, which is preferably the driving-axle. The cross-piece of the frame at the opposite ends of the side pieces F forms a support for one end of the field-magnet B.

C C are the pole-pieces of the field-magnet, which pole-pieces are provided with extensions c, of brass or other suitable material, resting on the cross-piece.

The opposite end of the field-magnet—that is, the yoke end—is sustained by the cross-pieces by means of a bar D, which is the yoke-piece to which the field-magnet cores are bolted, and is laterally extended, as shown, to permit it to be attached to the side pieces of the frame.

E is the armature of the electric motor, and G is the armature-shaft journaled in the frame F, as shown.

H is a shaft of the intermediate gear between the armature-shaft and the car-axle A.

The shaft H is likewise journaled to the frame, as shown. The caps of the journal-bearings are indicated at I I, &c.

The end of frame F opposite the end which is sleeved upon the car-axle is preferably elastically supported between cushions or springs S S, carried by a part of the truck-frame K, or by other suitable support.

While I have shown the electric motor as supported by extensions of a bar forming the yoke of the field-magnet, I do not limit myself to this special device, since the yoke end of the magnet might be supported from the frame F by other means without departing from my invention. I prefer to employ the particular manner described on account of its simplicity.

It will be seen that the bar D aids in giving rigidity to the frame in which the axes of the armature and core are supported.

While I have described the frame F as elastically supported from the truck-frame K, I do not limit myself to this particular method of suspension for said frame, since it might be supported from other parts of the vehicle without departing from my invention. I prefer, however, to suspend it from the truck-frame.

The extension c is part of the non-magnetic yoke which unites the ends of the pole-pieces C. The extension c may be either applied to the cross-piece F or may rest upon the same, so as to be capable of sliding freely on it. I prefer, however, to fasten it to the cross-piece F, so as to secure increased rigidity.

What I claim as my invention is—

1. The combination, with the supporting-frame carrying the journal-bearings for the armature-shaft, of the yoke-piece for the field-magnet extended laterally for attachment to said frame.

2. The combination, substantially as described, of a frame F, consisting of side pieces sleeved at one end on the car-axle and a uniting cross-piece at their opposite end, an electric motor having an armature journaled in said side pieces, and a field-magnet supported at its yoke end from the side pieces and at its pole end by extensions from said poles resting on the cross-piece.

3. The combination, substantially as described, of a frame consisting of side pieces

and a uniting cross-piece, with an electric motor having a field-magnet supported at its yoke end on the side pieces and at its pole ends by extensions from said poles resting upon the cross-piece.

4. The combination, substantially as described, of the frame F, consisting of side pieces and a uniting cross-piece, and an electric motor supported from and bolted to the side

pieces at one end and having an extension resting upon and bolted to the cross-piece.

Signed at New York, in the county of New York and State of New York, this 7th day of August, A. D. 1889.

EDWIN WILBUR RICE, JR.
